KENNETH S. BASKIN, OF CLEVELAND HEIGHTS, OHIO.

TABLE ATTACHMENT FOR SEATS.

1,351,548.

Specification of Letters Patent. Patented Aug. 31, 1920.

Application filed May 3, 1920. Serial No. 378,360.

To all whom it may concern:

Be it known that I, KENNETH S. BASKIN, a citizen of the United States, and residing at Cleveland Heights, in the county of 5 Cuyahoga and State of Ohio, have invented a new and useful Table Attachment for Seats, of which the following is a specification.

This invention relates to improvements in 10 table-attachments for seats, and pertains more especially to a table-attachment the table of which is adjustable forwardly and rearwardly and up and down and can be positioned horizontally or at an angle to a 15 horizontal plane.

One object of this invention is to produce 20 a highly practical table-attachment of the character indicated which is simple and durable in construction, attractive in appearance, and adequately supported without interfering with extensive knee-room for the occupant of the seat.

Another object is to facilitate the assemblage of the component parts of said 25 table-attachment and the manipulations required for readjustments of the table.

With these objects in view, and to attain 30 any other object hereinafter appearing, this invention consists in certain features of construction, and combinations and relative arrangements of parts, hereinafter described in this specification, pointed out in the claims, and illustrated in the accompanying drawings.

35 In said drawings, Figure 1 is a top plan of a table-attachment embodying my invention. Fig. 2 is a vertical section taken along the line 2—2, Fig. 1, looking forwardly. Fig. 3 is a horizontal section

40 taken along the line 3—3, Fig. 2 looking downwardly. Fig. 4 is a vertical section taken along the line 4—4, Fig. 2, looking outwardly. Fig. 5 is a vertical section taken along the line 5—5, Fig. 2, looking inwardly. Fig. 6 shows a portion of Fig. 4,

45 except that in Fig. 6 the table is inclined whereas in Fig. 4 the table is in a horizontal position. Fig. 7 is a section taken along the line 7—7, Fig. 6, looking in the direction indicated by the arrows. Fig. 8 is a vertical section taken along either line 8—8, Fig. 4. Portions are broken away in the drawings either to more clearly show the construction or to reduce the size of the drawings.

55 Referring to said drawings, 10 (see Figs. 1, 2, 3, 4 and 8) indicates a substantially

vertical standard which is preferably composed of a laterally facing upright flat piece of wood, and rendered rigid in any approved manner with a framework of a seat and arranged at the forward end and right-hand side of the seat-proper 12 which is preferably of wood, and said seat-proper has a forward extension 13 to which the standard is secured in any approved manner. The 60 lower portion of said standard is shown in Figs. 2 and 4 as extending below the member 13 and is adapted to rest on the floor. Said standard has its upper end portion, which is arranged above the seat-proper 12, 70 forming a substantially vertically arranged guideway which is engaged by a correspondingly arranged metal sleeve embracing and adjustable endwise of said portion of and extending above the standard 10 and forming 75 a vertically adjustable support, as will hereinafter more clearly appear, for a table 14. Said adjustable sleeve preferably comprises two metal plates 15 and 16 arranged at, and covering the inner side and outer 80 side respectively of the upper end portion of the standard 10, and said plates extend above the standard in any adjustment of said sleeve. Preferably the guideway-forming upper end portion of said standard has 85 its front and rear edges vertical and parallel and is therefore uniform in width, and the inner plate 15 (see Figs. 1, 2, 3 and 4) has flanges 17 overlapping said edges. The outer plate 16 is somewhat wider than the 90 inner plate 15 and has two laterally inwardly projecting flanges 19 overlapping the outer sides of the flanges 17 of said inner plate. Fig. 2 shows the flanges 17 and 19 extending from the upper end to the lower 95 end of the sleeve formed by the plates 15 and 16. Means for connecting together the lower end portions of the plates 15 and 16 (see Figs. 2, 4 and 8) comprise two substantially horizontal bolts which are spaced 100 transversely of the standard 10 and have their shanks 20 extending through vertical slots 21 in the standard and through bolt-holes 22 in the plates 15 and 16 and have their heads 23 overlapping the laterally inwardly facing side of the inner plate 15. On each bolt-shank 20 is threaded a nut 24 at the outer side of the outer plate 16. Obviously manipulation of the nuts 24 as required to loosen them in relation to the 105 standard 10 renders the plates 15 and 16, and consequently the sleeve formed by said 110

plates, free to be readjusted vertically, and said plates are secured to said standard in the desired vertical adjustment of the sleeve by manipulating said nuts as required to cause the inner plate 15 to be clamped to said standard by the bolt-heads 23 and to cause the outer plate 16 to be clamped to the standard by said nuts.

The table 14 is arranged at the front of 10 and above the seat 12 and extends over the upper ends of the plates 15 and 16 and somewhat beyond the outer side of the outer plate 16. Said table is provided at the bottom thereof, at said outer side of the 15 outer plate 16, with a metal bar 25 which extends transversely of said side of said outer plate, and said bar is provided at its top with a laterally and outwardly projecting flange 26 to which the table is removably secured by screws 27. The table 14 is arranged in the main at the laterally inwardly facing side of the inner plate 15 and pivotally connected, above the standard 10 and in proximity to the upper extremities 20 of the plates 15 and 16, to the upper end portions of said plates through the medium of a substantially horizontal pivotal pin 28 which (see Fig. 2) is arranged longitudinally of the table and applied as hereinafter 25 described and also employed in the pivotal connection to said plates of a brace arranged under the table at said side of said inner plate and having a body 30 extending diagonally from the bottom of the table at a point spaced laterally inwardly from the upper end of said inner plate downwardly and toward the lower portion of said inner plate. The body 30 of said brace has its lower end arranged opposite the inner side 30 of the standard 10 and has an arm 31 arranged next and abutting laterally against the laterally inwardly facing side of the inner plate 15 and extending vertically upwardly from said lower end of said body 45 to the upper end of said plate and consequently above said standard and preferably into close proximity to the table. The pivotal pin 28 extends through the upper end portion of the arm 31 and through the bar 50 25 and through slots 33 and 34 formed respectively (see Figs. 2 and 3) in the plates 15 and 16 above the standard 10 and rests on the bottoms of said slots which register and extend transversely of said plates in a 55 horizontal plane and permit readjustment of the table rearwardly and forwardly. The pin 28 is shown upset, as at 35, at the outer side of the bar 25 and extends through the brace-arm 31 and beyond the laterally inwardly facing side of said arm and has a head 36 at its inner end, and a washer 37 is shown interposed between said head and said arm. A tubular member 38 is mounted on the pin 28 between and braces apart the 60 plates 15 and 16.

The upper ends of the plates 15 and 16 are so contoured as to permit the table 14, when the table is free to be readjusted rearwardly and forwardly, to be actuated from the substantially horizontal position shown 70 in Figs. 1, 2 and 4 into the inclined position shown in Fig. 6, or vice versa. Means for securing the table 14 to the plates 15 and 16 in the desired adjustment of the table in relation to said plates (see Figs. 3 and 7) 75 preferably comprise a bolt having its shank 40 extending through the slots 33 and 34 and through slots 41 and 42 respectively formed in the bar 25 and brace-arm 31 and beyond the outer side of said bar. The slots 80 41 and 42 register therefore with the slots 33 and 34, and the last-mentioned bolt has a head 43 overlapping the laterally inwardly facing side of the brace-arm 31, and a nut 44 is threaded at the outer side of 85 the bar 25 onto the bolt-shank 40. By manipulating the nut 44 as required to loosen it in relation to the bar 25 the table 14 is rendered free to be readjusted in relation to the plates 15 and 16 and is secured 90 in the desired adjustment by tightening said nut against said bar. The slots 41 and 42 are curved and extend circumferentially of the axes of the table and hereinbefore mentioned brace and are concentric in relation 95 to said axes and arranged as required to permit actuation of the table, when the table is free to be readjusted, circumferentially of said axes, from the inclined position shown in Fig. 6 into the substantially horizontal position shown in Figs. 1, 2 and 4, or vice versa. A tubular member 45 is mounted on the bolt-shank 40 between and braces apart the plates 15 and 16.

To render the hereinbefore mentioned 105 brace more especially strong the body 30 of the brace is U-shaped in cross-section from the table to the lower end of the arm 31, and said arm has two spaced parallel flanges 46 extending from the upper end to 110 the lower end of the arm. Each flange 46 extends at its lower end into contiguity with the adjacent end of the adjacent upwardly projecting side member 47 of the body 30 of the brace, and said side member 47 of said 115 body and said flange 46 (see Figs. 1, 2 and 3) have their adjacent ends relatively contoured and arranged to effect the formation, between said ends, of a butt-joint 48 extending from the lower end of said arm upwardly and inwardly as shown in Fig. 2. Preferably the body 30 of the brace is provided at its upper end with a flange 49 which is arranged under and next the bottom of the table 14, and the table is secured 120 to said flange preferably removably by screws 50. Said brace has said flange 49 arranged farther from the table-carrying sleeve or adjustable support formed by the plates 15 and 16 than any other portion of 125 130

the brace, and said flange terminates at its extremity which is farthest from said sleeve or support in a member 51 projecting upwardly into and arranged transversely of 5 the table and is helpful in preventing strain on the screws 50.

By the construction and relative arrangement of the parts hereinbefore described my improved table-attachment for a seat is 10 rendered adequately strong and durable and avoids interference with a comparatively extensive knee-room for an occupant of the seat, and not unimportant to the most successful attainment of the hereinbefore stated 15 objects are the pivotal connection to the plates 15 and 16 of the brace and table well above the lower end of the body 30 of the brace and the arrangement in one and the same horizontal plane of the pivotal pin 28 20 and the bolt embraced by the member 45 and the extension of said bolt and said pin through the same horizontal slots 33 and 34 in said plates so as to render said brace and the table simultaneously adjustable trans- 25 versely of the plates. It will also be observed that the relative arrangements of the parts are such that in the inclined position of the table, shown in Fig. 6, the table and the brace are not only supported from 30 the plates 15 and 16 through the medium of the pivotal pin 28, but that the upper end walls of the slots 41 and 42 rest on the bolt-shank 40, as shown in Fig. 7.

What I claim is—

35 1. The combination, with a seat, a standard at the forward end and one side of the seat, a support adjustable up and down said standard, means for securing said adjustable support in the desired adjustment, and 40 a table extending over said adjustable support and arranged in the main at the laterally inwardly facing side of and pivotally connected to said support and movable, when free to be readjusted, circumferentially of its axis, from a substantially horizontal position into an inclined position or vice versa, of a brace arranged under said table and secured to the table at a point spaced laterally inwardly from the afore- 45 50 said adjustable support and extending from the table downwardly to said side of said support, said brace being pivotally connected to said adjustable support and having its axis coincident with the axis of the table, 55 said table and said brace being adjustable rearwardly and forwardly in a substantially horizontal plane, and means for securing the brace and the table to said adjustable support in the desired adjustment 60 of the table in relation to said support, the last-mentioned securing means and the aforesaid axes being in the same horizontal plane.

2. The combination, with a seat, a stand- 65 ard at the forward end and one side of the

seat and having its upper end portion forming a guideway, a sleeve embracing and adjustable endwise of the upper end portion of and supported from and extending above said standard, and a table extending over 70 the upper end of said sleeve and arranged in the main at the laterally inwardly facing side of the sleeve and pivotally connected above said standard to the sleeve, of a brace arranged under said table and secured to the 75 table at a point spaced laterally inwardly from said sleeve and extending from the table downwardly to said side of the sleeve, said brace being pivotally connected to said sleeve and having its axis coincident with 80 the axis of the table, and means for securing the table and the brace to said sleeve in the desired adjustment of the table circumferentially of said axes, said table and the brace being adjustable rearwardly and forwardly 85 in relation to the sleeve.

3. The combination, with a seat, a standard at the forward end and one side of the seat and having its upper end portion forming a guideway, a vertically adjustable support carried by said standard and comprising two plates arranged opposite the inner side and outer side respectively of said portion of and extending above the standard and connected together, one plate having 90 flanges overlapping the forward and rear edges of said portion of said standard and the other plate having flanges overlapping the outer sides of the first-mentioned flanges, and a table extending over the upper ends 100 of said plates and arranged in the main at the laterally inwardly facing side of the inner plate and pivotally connected above said standard to said plates, of a brace arranged under said table and secured to the 105 table at a point spaced laterally inwardly from said inner plate and extending from the table downwardly to said side of said inner plate, said brace being pivotally connected to said plates and having its axis 110 coincident with the axis of the table, and means for securing the table and the brace to said plates in the desired adjustment of the table circumferentially of said axes.

4. The combination, with a seat, a standard at the forward end and one side of the seat and having its upper end portion forming a guideway, a sleeve embracing and adjustable endwise of said portion of said standard and comprising two plates arranged opposite the inner side and outer side respectively of said portion of and extending above the standard and connected together, and a table extending over the upper ends of said plates and arranged in 120 the main at the laterally inwardly facing side of the inner plate and pivotally connected above said standard to said plates, of a brace arranged under said table and secured to the table at a point spaced later- 125 130

- ally inwardly from said inner plate and extending from the table downwardly to said inner plate, said brace being pivotally connected to said plates and having its axis 5 coincident with the axis of the table, and means for securing the table and the brace to said plates in the desired adjustment of the table circumferentially of said axes, said brace and said table being simultaneously 10 adjustable transversely of said plates.
5. The combination, with a seat, a standard at the forward end and one side of the seat, two plates arranged opposite the inner side and outer side respectively and adjustable endwise of and extending above said standard, and a table extending over the upper ends of said plates and provided at its bottom, at the outer side of the outer plate, with a bar extending transversely of 15 said side of said outer plate, said table being arranged in the main at the laterally inwardly facing side of the inner plate, of a pivotal pin extending through said bar and through said plates and inwardly beyond said side of said inner plate, a brace arranged under said table and secured to the table at a point spaced laterally inwardly from the inner plate and extending from the table downwardly to said side of 20 said inner plate and having a portion thereof embracing said pin, said pin forming the pivotal connection between said brace and the aforesaid plates, and means for securing the brace and the table to said plates in the desired adjustment of the table.
6. The combination, with a seat, a standard at the forward end and one side of the seat, two plates arranged opposite the inner side and outer side respectively and adjustable endwise of and extending above said standard, each plate being provided above said standard with a substantially horizontal slot which extends transversely of and laterally through the plate and is parallel 25 and registers with the corresponding slot in the other plate, and a table extending over the upper ends of said plates and provided at its bottom, at the outer side of the outer plate, with a bar extending transversely of 30 said side of said outer plate, said table being arranged in the main at the laterally inwardly facing side of the inner plate, of a pivotal pin extending through said bar and through the aforesaid slots and inwardly beyond said side of said inner plate and resting on the bottoms of said slots, and a brace arranged under the table and secured to the table at a point spaced laterally inwardly from said inner plate and 35 extending from the table to said inner plate and below the aforesaid slots and having a member embracing the aforesaid pin, and means for securing the table to the plates in the desired adjustment of the table in relation to the plates.
7. The combination, with a seat, a standard at the front and one side of the seat, two plates at the inner side and outer side respectively of and supported from and extending above said standard and each provided above said standard with a slot which extends transversely of and laterally through the plate and is parallel and registers with the corresponding slot in the other plate, and a table arranged in the main at the laterally inwardly facing side of the inner plate and extending over said plates and having a bar extending transversely of the outer side of the outer plate, a pivotal pin extending from within said bar through 70 and inwardly beyond said inner plate and through and resting on the bottoms of said slots, and a brace arranged under and secured to the table and having a member embracing said pin, said pin-embracing brace-member and said bar having curved slots registering with the first-mentioned slots and arranged to permit readjustment of the table circumferentially of said pin, of a bolt having its shank extending through all of 75 said slots and through and outwardly beyond said bar and through said pin-embracing brace-member and having a head overlapping the laterally inwardly facing side of said pin-embracing brace-member, a nut threaded onto said shank at the outer side of said bar, and a tubular member on said shank between and bracing apart the aforesaid plates.
8. The combination, with a seat, a standard at the forward end and one side of the seat, two plates at the inner side and outer side respectively of and supported from and extending above said standard, a table extending over said plates and arranged in the main at the laterally inwardly facing side of the inner plate and having a bar extending transversely of the outer side of the outer plate, and a pivotal pin extending from within said bar through said plates and inwardly beyond the aforesaid side of the inner plate, of a brace arranged under the table and secured to the table at a point spaced laterally inwardly from the inner plate and having a portion thereof embracing said pin, means for securing the brace and the table to said plates in the desired adjustment of the table circumferentially of 100 said pin, the brace being provided at its upper end with a flange arranged under and next the table, and screws securing the table to said flange, said flange being farther from said plates than any other portion of the brace and provided at its extremity which is farthest from the aforesaid inner plate with a member which projects upwardly into the table.
9. The combination, with a seat, a standard at the forward end and one side of the seat, a support adjustable up and down the 105
- 110
- 115
- 120
- 125
- 130

- upper end portion of and extending above the standard, means for securing said adjustable support in the desired adjustment, and a table extending over said adjustable support and arranged in the main at the laterally inwardly facing side of and pivotally connected to said support and movable, when free to be readjusted, circumferentially of its axis, of a brace arranged under the table and having an angular member which is secured to the table at a point spaced laterally inwardly from said adjustable support and extends from the table downwardly to a point opposite the inner side of the aforesaid standard and also having an arm which extends upwardly from the lower end of said member and abuts laterally against the aforesaid side of and is pivotally connected to said adjustable support and has its axis coincident with the axis of the table, and means for securing the table and said arm to said adjustable support in the desired adjustment of the table in relation to said support.
10. The combination, with a seat, a standard at the forward end and one side of the seat, a support adjustable endwise of the upper end portion of and extending above and carried by the standard, and a table extending over said adjustable support and arranged in the main at the laterally inwardly facing side of said support and provided at the outer side of the upper end portion of said support with a bar which extends transversely of said outer side of said support, and a pivotal pin arranged longitudinally of the table and extending from within said bar through said adjustable support and beyond the laterally inwardly facing side of said support, of a brace arranged under the table and having an angular member which is secured to and extends downwardly from the table at a point spaced laterally inwardly from said adjustable support and also comprising an arm which extends from the lower end of said member upwardly into proximity to the table and embraces said pin, and means for securing the table and the brace to said adjustable support in the desired adjustment of the table in relation to said support.
11. The combination, with a seat, a standard at the front and one side of the seat, a support adjustable endwise of the upper portion of and extending above and carried by the standard, and a table extending over said adjustable support and arranged in the main at the laterally inwardly facing side of and pivotally connected to said support and having its axis arranged longitudinally of the table, of a brace arranged under the table and having an angular member which is U-shaped in cross-section and secured to and extends downwardly from the table at
- a point spaced laterally inwardly from said adjustable support and also comprising an arm which extends upwardly from the lower end of said member and is arranged at the laterally inwardly facing side of said support and has spaced flanges which project toward said body and extend longitudinally of the arm, said arm being pivotally connected at its upper end portion to said adjustable support and having its axis coincident with the axis of the table, and means for securing the table and the brace to said adjustable support in the desired adjustment of the table in relation to said support, each flange of the aforesaid arm being contiguous at its lower end to the adjacent end of the adjacent upwardly projecting side member of the body of the brace, and said side member of said body and said flange having their adjacent ends relatively contoured and arranged to effect the formation, between said ends, of a butt-joint extending from the lower end of said arm upwardly and inwardly.
12. The combination, with a seat, a standard at the forward end and one side of the seat, two plates arranged at the inner side and outer side respectively of and supported from and extending above the standard and each provided with a substantially horizontal slot which extends laterally through the plate and registers with the corresponding slot in the other plate, and a table extending over said plates and arranged in the main at the laterally inwardly facing side of the inner plate and having a bar arranged at the outer side of and opposite the slot in and extending transversely of said outer plate, of a brace arranged under the table and having an angular member which extends from the table downwardly toward the inner plate and comprising an arm extending opposite the slot in said inner plate, a pivotal pin extending from within said arm through said slots and into the aforesaid bar, a bolt which has a head overlapping the laterally inwardly facing side of said arm and has its shank extending through said arm and through said slots and through said bar and beyond the outer side of said bar, and a nut threaded onto said shank at said side of said bar, said bar and said arm being provided at said bolt with curved slots registering with the first-mentioned slots and arranged to permit readjustment of the table circumferentially of the aforesaid pin.
- In testimony whereof, I sign the foregoing specification, in the presence of two witnesses.
- KENNETH S. BASKIN.
